US0D1047287S

(12) **United States Design Patent** (10) Patent No.: **US D1,047,287 S**
(45) Date of Patent: ** Oct. 15, 2024

(54) **MOTORCYCLE HELMET**

(71) Applicant: **SHARK**, Marseilles (FR)

(72) Inventor: **Frédéric Dobbelstein**, Auriol (FR)

(73) Assignee: **SHARK**, Marseilles (FR)

(**) Term: **15 Years**

(21) Appl. No.: **35/516,982**

(22) Filed: **Apr. 13, 2023**

(80) **Hague Agreement Data**

Int. Filing Date: **Apr. 13, 2023**

Int. Reg. No.: **DM/228212**

Int. Reg. Date: **Apr. 13, 2023**

Int. Reg. Pub. Date: **Apr. 28, 2023**

(57) **CLAIM**

The ornamental design for a motorcycle helmet as shown and described.

DESCRIPTION

1. Motorcycle helmet

1.1: Front

1.2: Right

1.3: Rear Perspective

1.4: Rear

1.5: Top perspective

1.6: Top

1.7: Bottom Perspective

The evenly-spaced broken lines depict portions of the motorcycle helmet that form no part of the claimed design. The long-short-long broken lines depict boundaries of the claimed subject matter and form no part of the claimed design.

1 Claim, 7 Drawing Sheets
